ABSTRACT OF THE DISCLOSURE

A desk-mountable, hand-operated, letter-folding, envelope-stuffing structure in which a slide having articulated wall segments is manually moved in one direction to fold the letter and is further moved in the same direction to place the folded letter in an envelope.

SUMMARY OF THE INVENTION

The invention provides an economical desk-mountable assembly, including a base, a slide with articulated walls, a finger arrangement and an envelope-supporting end pocket, whereby manual movement of the slide in one direction articulates the walls and actuates the finger arrangement to fold a letter sheet and continued movement of the slide in the same direction transfers the folded sheet into the pocket from whence the envelope, with the letter therein, may then be manually removed. Movement of the slide in the opposite direction resets the assembly.

This invention relates to the field of office machines 30 and has particular relation to a desk-mountable, manually-operable means for folding paper sheets, such as letters and the like, and for stuffing the same into envelopes.

One purpose of the invention is to provide a simplified, compact letter-folding and envelope-stuffing mechanism.

Another purpose is to provide a letter-folding, envelope-stuffing mechanism of maximum economy in construction and use.

Another purpose is to provide manually-operable means for folding a letter and stuffing the same in an envelope 40 in a single motion.

Other purposes may appear from time to time during the course of the specification and claims.

The invention is illustrated more or less diagrammatically in the accompanying drawings, wherein:

FIGURE 1 is a front elevation;

FIGURE 2 is a top plan view with parts in one position;

FIGURES 3, 4, 5 and 6 are top plan views with parts in progressively further positions in the operation of the 50 invention;

FIGURE 7 is a detail view on an enlarged scale;

FIGURE 8 is an end view;

FIGURE 9 is a detail view on an enlarged scale;

FIGURE 10 is a detail view on an enlarged scale;

FIGURE 11 is a detail view on an enlarged scale; and

FIGURE 12 is a view on the line 12—12 of FIGURE 11.

Like parts are indicated by like numerals throughout the specification and drawings.

Referring now to the drawings, the numeral 1 generally designates a base suitable for positioning on a table or desk. A longitudinal slot 2 is formed in the upper surface of base 1 and slide 3 is movable therein. The slide 3 is movable adjacent the lower forward surface of a fixed vertical wall 4 upstanding on the base 1.

Upstanding on slide 3 along the forward face of wall 4 is a letter-folding structure comprising a movable end pocket segment 5. Extending from the pocket 5 in substantial parallel relation with the wall is a handle 6. The end pocket 5 is open in its direction of movement toward letter-folding position. Handle 6 extends from pocket 5

2

in the opposite direction. Secured to the forward wall or outer wall of end pocket 5 and to the forward edge thereof is a pair of articulated letter-folding panels 7, 8. Panel 7 is hinged to pocket 5, as indicated at 9, and to panel 8, as indicated at 10. The forward edge of panel 8 is urged toward wall 4 by a panel 11 hinged, as at 12, and urged by spring 13. A stop 14 is mounted on base 1 to limit outward movement of panel 11. Panel 11 is hinged as at 12 to a fixed pocket-forming wall 15 secured in spaced parallel relationship with wall 4 by brackets 15a and upwardly spaced from base 1, as may be best seen in FIGURE 1. Wall 15 is actually in spaced parallel relationship with an end portion 4a of wall 4, which wall portion has its lower edge also upwardly spaced from base 1. The pocket formed by wall portions 15, 4a is indicated generally by the numeral 16. The pocket 16 is open at both ends to receive as at 16a a folded letter and portions of pocket 5 and panels 7, 8 and for outward extension of a portion of the folded letter outwardly of the pocket 16 and through its end opening indicated at 16b. A recess 17 is formed in the end surfaces of wall portions 4a, 15 for purposes described below. As shown in dotted lines in FIGURES 1—4, the pocket structure 16 is formed and dimensioned to be received within an open envelope inserted thereon.

The rear vertical wall 4 is broken, intermediate its ends, for mounting of a finger member or finger panel 20. The panel 20 is urged outwardly of wall 4 and toward panel 7, 8 by spring 21. A lock element 22 is slidably supported in wall 4, as may be best seen in FIGURE 10, for holding finger panel 20 in alignment with wall 4. Lock 22 has an ear or cam portion 23 extending forwardly of wall 4 and positioned for engagement with a catch 24 pivotally carried by slide 3, as best seen in FIGURES 11 and 12. The catch 24 dangles by gravity from slide 3 for movement against a slide surface 25 of slide 3 when the slide is moved in one direction and against surface 26 when the slide is moved in the opposite direction.

As best seen in FIGURES 9 and 10, an abutment 27 is yieldingly urged into a position outstanding from wall 4 by a suitable spring 28. A recessed side wall portion 3a of slide 3 is engageable with abutment 27 to cam the same into alignment with wall 4 as the slide moves in one direction.

Whereas there has been shown and described an operative form of the invention, it should be understood that this showing and description are to be taken in an illustrative or diagrammatic sense only. There are many modifications in and to the invention which will be apparent to those skilled in the art and which will fall within the scope and spirit of the invention.

The use and operation of the invention are as follows:

Wall 4, with finger panel 20 closed, forms with pocket 5 and panels 7 and 8 an upwardly open, sheet-receiving chamber, one end of which is formed of the pocket 5 having a closed rear end and opposed, spaced wall surfaces 5a, 5b. A sheet of paper to be folded, such as a letter, is inserted downwardly into the chamber or space between wall 4 and the panels 7 and 8 and into the pocket 5 as shown in broken lines in FIGURES 3—4. With the letter so placed one end edge of the letter is engageable with the closed rear end of pocket 5 and the opposite end edge of the letter is engageable with abutment 27. Similarly, the forward edge of panel 8 is engageable with abutment 27. An envelope is placed over pocket 16 as shown in FIGURES 1—7.

The operator grasps handle 6 and moves it along the front surface of wall 4 or to the right as the parts are shown in the drawings. The resulting movement of slide 3 brings catch 24 into engagement with ear 23 and surface 25 to cam lock 22 downwardly and thus to unlock

finger panel 20. Thereupon the spring 21 moves panel 20 toward the letter and toward folding panels 7, 8 to initiate a fold in the letter. Simultaneously, movement of handle 6 produces a movement of pocket 5 to flex the letter and to articulate panels 7 and 8 into the positions indicated in FIGURES 2-6, the letter and panel 8 having their forward edges restrained by abutment 27. It will be observed that panel 7 is moved rearwardly upon pocket 5 and panel 8 is closed upon panel 7, folding the letter into three folds, the spring-urged panel 11 urging panel 8 toward panel 7 as handle 6 is further moved to the right as the parts are shown. Portion 3a of slide 3 moves abutment 27 into wall 4 and slide 3 holds abutment 27 out of the way of the letter, pocket 5 and panels 7, 8 as movement of slide 3 continues. When inner wall 5a of pocket 5 meets finger panel 20 it closes the same, as indicated in FIGURE 4, and upon closure of panel 20 the lock 22 engages therewith to retain the panel 20 in closed position.

Continued movement of handle 6 to the right, as the parts are shown in the drawings, moves the then folded panels 7, 8 and the pocket 5 into the fixed end pocket 16. It will be observed that the fold of the letter shown in broken lines extends forwardly of the hinge point 9 between pocket 5 and panel 7. Thus at least a portion of the folded letter extends beyond the pocket 5 and panels 7, 8 within pocket 16, the said letter portion being in alignment with the recess 17. The operator then grasps the envelope on opposite sides of the recess 17 to grasp the envelope and the letter portion in alignment with the recess 17. The operator then merely withdraws the envelope from the pocket 16, or to the right as the parts are shown in the drawings; the letter, being grasped through compression of the envelope by the operator, enters the envelope and leaves the pocket 16 as the envelope is withdrawn therefrom.

The operator then retracts the handle 6 into the position shown in FIGURE 1, or to the left as the parts are shown in the drawings. Catch 24, having full freedom to do so, will merely ride over the ear 23 and up against surface 26 of slide 3 and out of the way. Thus panel 20 will remain locked in alignment with wall 4 and out of the way of a new sheet to be inserted for folding.

Similarly, as slide 3 moves to the left, the abutment 27 will be repositioned by spring 28 in the position shown for example in FIGURE 9.

Thus movement of the handle 6 in one direction is effective to fold and position a letter within the internal

area of an envelope carried on pocket 16. Withdrawal of the envelope in the same direction is effective to produce an envelope with the folded letter therein and a single movement of the handle 6 in the opposite direction resets the assembly of the invention for repeated operation.

There is claimed:

1. A sheet-folding assembly including a base, a fixed wall extending from said base, a slide mounted for movement on said base along the face of said wall in spaced relation therewith, said wall and slide forming a sheet-receiving chamber, said slide including a plurality of articulated panels, movement of said slide in one direction being effective to articulate at least some of said panels outwardly from said wall to produce an initial fold in said sheet, further movement of said slide in said direction being effective to articulate at least some of said panels inwardly toward said wall to complete said fold.
2. The structure of claim 1 characterized by and including a finger assembly extendable into said chamber to move said sheet toward said panels.
3. The structure of claim 1 characterized by and including a pocket structure positioned on said base to receive a folded sheet from said slide in response to further movement of said slide in said direction.
4. The structure of claim 3 wherein said pocket structure is externally dimensioned to fit within an envelope and having a forward opening to receive a folded sheet and a rear opening for passage therethrough of said sheet.
5. The structure of claim 3 wherein said pocket structure includes a folded sheet exposing configuration at its distal end whereby said folded sheet may be drawn outwardly from said structure in the direction of said slide movement.
